FIG. 1.

FIG. 4.

FIG. 2.

FIG. 3.

FIGURE 1 is a face view of a track wheel embodying our new design, and appearing in a left side elevational view of, and shown mounted on a track frame of, a tractor;

FIGURE 2 is a face view similar to FIGURE 1, but drawn to enlarged scale;

FIGURE 3 shows a fragmentary detail in cross-section, with the view directed radially outwardly, and the section taken along the lines III-III of FIGURE 2; and

FIGURE 4 shows the fragmentary detail of FIGURE 3, but is a perspective representation.

The dominant features of the design reside in the portions shown in full lines, and the tractor shown fragmentarily in broken lines in FIGURE 1 is intended for illustrative purposes only.

It is to be understood that the design shown in full lines in FIGURES 1 and 2 continues through the circumference of the wheel.

We claim:

The ornamental design for a track wheel, as shown and described.
